UNITED STATES PATENT OFFICE

ARVID RUDEBERG, OF STOCKHOLM, SWEDEN, ASSIGNOR TO AKTIEBOLAGET MENITOR,
OF STOCKHOLM, SWEDEN

PROPELLER

Application filed July 24, 1929, Serial No. 380,487, and in Sweden August 8, 1928.

The present invention relates to a propeller for driving ships and other vessels through water and in which the working surfaces of the blades are convex in the portions next to the hub and concave in the outer portions, so that the water, into which the concave portions cut, is directed outwards from the propeller shaft, thus preventing an accumulation of water around the propeller shaft and 10 an eddying movement in the water.

In the accompanying drawings, Fig. 1 shows the propeller seen from astern, and Fig. 2 a longitudinal section of one of the propeller blades. Fig. 3 is a cross section 15 through the convex portion, and Fig. 4 a cross section through the concave portion of the blade.

The central line of the root of the blade is at an angle to the hub in such a manner, 20 that the leading edge 1 of the blade is in front of the rear edge 2 in the axial direction, and this angle increases towards the outer portion of the blade.

The working surface of the blade is convex up to a certain distance from the hub 25 and then gradually merging into an outer concave portion 4, so that a longitudinal section through the working surface shows a line in the form of an S. The convex portion of 30 the blade is designated by 3.

Having now described my invention, what I claim as new and desire to secure by Letters Patent is:—

A propeller having a hub and blades extending therefrom, each of said blades having a root portion adjacent the hub of flatly ovate form arranged with its longer axis in a plane radial to the axis of the hub and at an acute angle thereto, the outer portion of 35 each blade being convexly curved on one side and concavely curved on the other side in both longitudinal and transverse directions with the curved surfaces merging smoothly into the root portion of the blade whereby 40 the rear surface of the blade is reversely curved from hub to tip in longitudinal section, the front and rear faces of said blade tapering gradually toward each other from hub to tip longitudinally and from the center 45 to the leading and trailing edges transversely,

the tip of said blade being located substantially in a plane perpendicular to the axis of the hub and passing through the center of the blade root at the hub.

In testimony whereof I have signed my 55 name to this specification.

ARVID RUDEBERG.
